UNITED STATES PATENT OFFICE.

FRANK L. JOHNSON, OF MCKEESPORT, PENNSYLVANIA.

DESIGN FOR A COAT AND HAT HOOK.

SPECIFICATION forming part of Design No. 30,770, dated May 16, 1899.

Application filed April 21, 1899. Serial No. 713,978. Term of patent 3½ years.

To all whom it may concern:

Be it known that I, FRANK L. JOHNSON, a citizen of the United States of America, residing at McKeesport, in the county of Allegheny and State of Pennsylvania, have invented a certain new and useful Design for Hooks, of which the following is a specification, reference being had therein to the accompanying drawing.

10 This invention relates to a certain new and original design for hat and coat hooks.

In the drawing I have shown a perspective view of my new design, and, as shown in the view, the leading or material feature of my 15 design consists of the curved C-shaped hook A and the upper supporting-hook B.

The entire design consists of the shank C, having the screw-threaded pointed end c, the

shank being bent upward and then downward at substantially right angles to form the upper hook B and then bent toward and then away from the pointed end c in a substantially V shape, as at D, and then curved into the C-shaped hook A.

Having described my invention, what I claim as new, and desire to secure by Letters Patent, is—

The design for a coat and hat hook, as herein shown and described.

In testimony whereof I affix my signature in the presence of two witnesses.

FRANK L. JOHNSON.
